UNITED STATES PATENT OFFICE.

HERBERT S. MILLS, OF CHICAGO, ILLINOIS.

VENDING-MACHINE.

1,002,535.

Specification of Letters Patent.

Patented Sept. 5, 1911.

Application filed May 26, 1911. Serial No. 629,689.

To all whom it may concern:

Be it known that I, HERBERT S. MILLS, a citizen of the United States, residing at Chicago, in the county of Cook and State of Illinois, have invented a new and useful Improvement in Vending-Machines, of which the following is a specification.

The object of my invention is to provide a novel construction of vending machine in the class employing a magazine for holding a stacked supply of the article to be delivered from the base of the stack each time the machine is worked upon being rendered operative by inserting into it a coin of proper denomination.

I have devised my improvement more especially for vending sanitary drinking cups; and it is hereinafter described in that particular connection and so illustrated in the accompanying drawings, in which—

Figure 1 is a view of the machine in front elevation with a portion of the front casing-wall broken away to disclose parts of the operating mechanism; Fig. 2 is a section on line 2, Fig. 1, showing the under side of the casing-top, which contains an opening and forms the base of the magazine provided with supports at intervals about the opening for sustaining the stack of folded cups from the bottom of which the delivery is produced; Fig. 3 is a perspective view of one of the folded sanitary drinking cups with a portion broken away to show a detail of construction; Fig. 4 is a partly broken section on line 4, Fig. 1, illustrating in its normal condition the coin-controlled mechanism for actuating the delivery-mechanism of the machine, and Fig. 5 is a similar view showing the coin-controlled mechanism under actuation; Fig. 6 is a section on line 6, Fig. 4; Fig. 7 is an enlarged section on line 7, Fig. 1, showing the delivery-mechanism; Fig. 8 is a section on line 8, Fig. 7, and Fig. 9 is a plan view regarded at the line 9, Fig. 8.

The drinking-cup 10 (Fig. 3) to be vended by my improved machine, is made of moisture-proof (paraffined) paper out of a suitable blank flaring from its transverse center toward its ends and folded upon itself at the center, with flaps 11 on the edges of one section folded over and cemented to the edge-positions of the other section. Thus, in the normal condition of the cup, the sections are flatwise together as represented.

The case 12 is shown of rectangular shape

with a removable front wall 14 equipped with a suitable key-operated lock 13 and containing a lower delivery-opening 15. In the top 16 of the case is formed an opening 17 surrounded by a flange 18 and of the general shape of a flat cup 10, with lugs 19 projecting inwardly, one from each edge, to form an open seat for a stack of the cups through which the lowermost cup in the stack may be readily withdrawn. The top 16 affords the base of a magazine, which may be formed of a cage composed of upright rods 20 rising at suitable intervals from the flange 18 and connected at their upper ends, to tie them stably together, by a band 22 fastened by nuts 23 on the rods; and a cylindrical hood 24, preferably of glass to render it transparent for displaying the contents of the magazine, and provided with a permanent metal cover 25, envelops the cage and is fastened at a metal flange 26 about its lower edge to the top 16.

In the top near one corner of the case is a coin-insertion slot 27 at which extends downwardly on the inner side of the adjacent side-wall of the case a coin-chute 28. The lower, discharge end of the chute 28 registers with a recess 29 in the segmental head 30 of a lever 31 fulcrumed near its lower end, at 32, to the side-wall of the case, adjacent to a stop 33 for limiting the return-movement of the lever, the lower end of which carries a finger 34 connected by a spiral spring 35 with a stud 36 on said wall. To this same wall is fulcrumed between its ends a lever 37 carrying on the inner face of its outer-end portion an obliquely extending lug 38 against which bears the lower, headed end of a vertical push-rod 39 working through the top of the case in a bearing 40 and provided on its outer end with a knob 41.

It will be noted that by depressing the operating push-rod, the lever 27 is forced against the head 30 with the latter upon a dead center and does not, therefore turn the head; whereas by introducing a coin 42 (Fig. 4) through the chute to lodge in the head-recess 29 and protrude beyond it, the lever, by depressing it, encounters at the lug 38 thereon, the coin behind its vertical center, and thus through the interposition of the coin turns the lever 31 on its fulcrum against the retractive force of the spring 35. The machine is therefore inoperative until a coin is introduced into the head 30.

The lever 37 passes, toward its inner end, across a lower stop 43, to which and a similar upper stop 44 (both on the aforesaid side-wall of the case) extends a concavely-5 segmental rack 45 to be engaged by a spring-pressed pawl 46 on the lever to prevent return thereof, under the retractive force of a spring 47, to its normal position from any intermediate one between that position and the tripping position hereinafter described.

On the lever 37 near its inner end is pivotally secured a spring-pressed dog 48, which projects beyond that end of the lever to perform the tripping purpose upon the adjacent end of a relatively-short arm 49 extending into the path of the dog from one end of a rock-shaft 50 fulcrumed in bearings on the back of the case and having a relatively longer arm 51 extending forwardly, parallel with the arm 49, from the opposite end of the rock-shaft.

On the bottom of the case is fastened, at a foot 52, a vertically slotted standard 53 in which is reciprocably confined a bar 54 provided on its outer face with a stud 55 which projects through the relatively short slot in the back of the standard and is connected with a stud 56 on the standard near its lower end by a coiled retracting-spring 57. An angular arm 58 secured at the slot in the standard to the inner face of the reciprocating bar 54, carries on its upper end a suction-cup 59, preferably of soft-rubber, and has a stud 60 projecting from near its lower end to extend across, and under the adjacent end of the arm 51. The position of the cup 59 is in line with the center of the magazine-opening 17.

With a stack 61 of the flat drinking-cups, 40 10 in the magazine, and preferably having, a weight 62 resting upon it for its resistance to the action of the pneumatic cup 59, the machine is operated as follows: Upon inserting a suitable coin or token into the slot 45 27 to lodge in the head 30, and depressing the push-rod to engage the coin, as described, the lever 31 is turned on its fulcrum by the turning of the lever 37 and discharges the coin out of the head into the bottom of the 50 case, where a suitable receptacle (not shown) may be provided to receive it; and the depression of the outer end of the lever 37 from the normal position shown in Fig. 4, to the position shown in Fig. 5 raises its inner 55 end to cause the dog 48 to encounter the adjacent end of the arm 49 and thereby turn the rock-shaft 50 to raise the arm 51. In rising, the arm 51 encounters the horizontal section of the arm 58 which carries 60 the cup 59 and raises the bar 54 to impinge the cup centrally against the lowermost drinking-cup 10 in the stack. The operation is so timed that just after the suction-cup is pressed against the bottom of the 65 stack, the dog 48 clears and trips the arm

49 when, also, the pawl 46 has cleared the rack 45, permitting the spring 47, upon the operator's releasing the push-rod, to retract the lever 37 to its normal position (Fig. 4). Upon the release of the arm 49 from the 70 dog 48, the spring 57 suddenly and forcibly retracts the bar 54 and cup 59 causing the latter in descending to pull away from the stack and off the seating lugs 19 through the magazine base-opening 17 the lowermost cup 75 10 by the suction-action thereon of the cup 59. The folded drinking-cup thus pulled out drops on a curved chute-plate 63 extending from the back of the casing through the opening 15 in its front wall, beyond 80 which it forms a delivery-tray 64 (Fig. 7) for the lodgment of the vended drinking-cup where it is accessible for removal. Where the chute-plate extends over the suction-cup and its attendant mechanism, it is 85 cut out, as shown in Fig. 7, to provide an opening 65 through which to permit the delivery-mechanism to work.

What I claim as new and desire to secure by Letters Patent is—

1. In a vending-machine, the combination of a case provided with a top-opening adapted to seat about it a stack of articles to be vended, a delivery-opening and a chute leading thereto, a magazine for the stack, a delivery-device in the case comprising a vertically-reciprocating spring-retracted suction-cup raisable against the lowermost article in the stack to withdraw it therefrom by the spring-retraction and means for raising said cup, for the purpose set forth.

2. In a vending-machine, the combination of a case provided with a top-opening adapted to seat about it a stack of articles to be vended, a delivery-opening and a chute leading thereto, a magazine for the stack, a delivery-device in the case comprising a standard, a spring-retracted bar reciprocably confined in the standard and a suction-cup extending from the bar, and means for raising the bar to impinge the cup against the lowermost article in the stack to withdraw it therefrom by the spring-retraction, for the purpose set forth.

3. In a vending-machine, the combination of a case provided with a top-opening adapted to seat about it a stack of articles to be vended, a delivery-opening and a chute leading thereto, a magazine comprising a set of hood-covered upright rods spaced apart about said opening, a delivery device in the case comprising a vertically-reciprocating spring-retracted suction-cup raisable against the bottom of the stack to withdraw therefrom the lowermost article and means for raising said cup, for the purpose set forth.

4. In a vending-machine, the combination of a case provided with a magazine-covered top-opening adapted to seat about it a stack of articles to be vended, a delivery-opening

and a chute leading thereto, a delivery-device in the case comprising a standard, a spring-retracted bar reciprocably confined therein and a suction-cup on an arm extending from the bar, and a rock-shaft journaled in the case and having an arm extending across the cup-carrying arm, and means for

turning said shaft to raise its said arm against and thereby raise the cup carrying arm, for the purpose set forth.

HERBERT S. MILLS.
